UNITED STATES PATENT OFFICE

JOSEPH S. DUNCAN AND HENRY E. HUBBARD, OF CHICAGO, ILLINOIS, ASSIGNEES TO
ADDRESSEOGRAPH COMPANY, OF WILMINGTON, DELAWARE, A CORPORATION OF
DELAWARE

PRINTING MACHINE

Application filed December 3, 1927. Serial No. 237,426.

This invention relates to automatic printing machines which will print addresses on magazines and other publications from individual printing devices which are successively fed through the machine and which may be automatically selected for printing or for skipping by suitable selector devices; and the invention particularly relates to means for grouping the addressed magazines according to a predetermined classification.

For example, if the magazines are to be sent to various towns it is desirable that the magazines for each town be grouped together and bundled for delivery to that particular town. This method saves time in handling and in shipping, and avoids the necessity of sorting the magazines at the post office.

The grouping of the magazines is accomplished by providing a tab on the first or the last printing device within a series for a group. Every printing device so tabbed will cause the grouping mechanism to operate a jogger and jog one magazine in the continually moving line of magazines as they are being carried from the machine, and the jogged magazine will indicate the beginning or the ending of a group. This enables the operator to readily sort the grouped magazines in removing them from the machine and each group may then be separately bundled for shipping and delivery.

The invention may be applied to various types of machines but it is particularly adapted for machines such as are disclosed and claimed in our copending applications, Serial No. 212,424 and 212,425, both filed August 12, 1927.

The primary object of the invention is to provide a novel automatic grouper controlled by certain address printing devices whereby the addressed magazines will be periodically jogged, as they are being carried away from address printing position, according to a predetermined classification.

Another object of the invention is to provide an article grouper which is simple in construction, which can be readily and economically manufactured, and which is adapt-

ed to be applied to existing printing machines.

The invention has other objects in view incidental to these primary objects which will appear hereafter in the detail description of a selected embodiment of the invention chosen for illustration in the accompanying drawings in which the views are as follows:

Fig. 1 is a front elevation of a printing machine with the invention applied thereto. 60

Fig. 2 is a plan view of the machine shown in Fig. 1.

Fig. 3 is a detail section view on the line 3-3 of Fig. 2.

Fig. 4 is a similar view on the line 4-4 of Fig. 2.

Figs. 5 and 7 are enlarged detail sectional views on the line 5-5 of Fig. 2 showing some parts in different positions.

Figs. 6 and 8 are enlarged detail sectional views showing the latch lever and some of the cooperating parts in different positions. 70

Fig. 9 is an enlarged detail front elevation showing the jogger and its operating mechanism. 75

Fig. 10 is a longitudinal sectional view of some of the parts shown in Fig. 9.

Fig. 11 is a transverse sectional view of some of the parts shown in Fig. 9.

Referring to the drawings 1 designates the printing machine such as is disclosed in the aforesaid copending applications and it has a frame 2 and a bed 3. A cam shaft 4 mounted in the frame and driven from the drive shaft 5, drives the longitudinal shaft 6 through the chain of gears 7 and the bevel gear 8, Fig. 1. 80

An address printing device magazine 9 on the frame carries a stack of printing devices 10 which are adapted to be fed intermittently one at a time from the bottom of the stack to printing position. The printing devices are of the usual type and pass through certain selector mechanism where they are either selected to be printed or to be skipped. Some of the devices are provided with a tab 10' which controls the movement of a pawl 11, Fig. 3, which projects upward through the bed of the machine. Each printing device rides over and de- 100

presses the pawl. If the printing device is not provided with a tab 10' the pawl returns to up position immediately after the printing device rides off of the pawl; if the printing device has a tab 10' this tab will continue to hold the pawl depressed after the printing device proper has ridden off of the pawl and while it is temporarily at rest in position adjacent the pawl. This continued depression of the pawl sets in operation the parts which result in jogging the magazine which receives an address impression from the printing device having the tab.

The tripper pawl 11, Figs. 3, 4, 6 and 8, is carried by a tripper 12 having a notched end 13 which is engaged by a lug 14 on the latch lever 15 pivoted at 15'. A spring 16 holds the tripper in normal position in engagement with the latch lever when the tripper pawl 11 is in its raised position as shown in Figs. 3 and 6.

A rod 17 is connected at one end to the upper end of the latch lever 15 and at its other end to an arm 18 rigid on the rock shaft 19, Figs. 3 and 4. When the tripper is disengaged from the latch lever a spring 20 connected to the rod 17 and to the frame, Fig. 3, pulls the rod and the latch lever to the position shown in Fig. 4, and at the same time rocks the rock shaft 19 for operating the jogging mechanism.

The rock shaft 19 is mounted in suitable bearings on the machine frame and has fixed thereto an angle lever 21 to which is pivoted a roller 22 engaging a restoring cam 23 fixed to the longitudinal shaft 6, Figs. 4, 5 and 7. A link 24 has one end pivoted at 25 to the angle lever and its other end pivoted at 26 to the pawl releasing arm 27 which is pivoted on the stud shaft 28 mounted in the casting 28' fixed to the bed of the frame. Through these parts the pawl 11 is normally held in up position, Fig. 6, the roller 22 being in normal position out of operative relation to the restoring cam, Fig. 5, and the tripper 12 being engaged with the latch lever 15, Fig. 6. When the pawl 11 is depressed by the tab 10', Fig. 8, the tripper 12 is disengaged from the latch lever and the roller 22 is held in operative engagement with the restoring cam by spring 20, Fig. 7.

A sleeve 29, Fig. 10, is loosely mounted on the longitudinal shaft 6 and carries a jogger cam 29', having a stud 30 thereon upon which a pawl 31 is pivoted and carries a pawl roller 32, Figs. 5, 7, 9. A sleeve 33 is pinned on the shaft 6 between the restoring cam 23 and the jogger cam 29' and it has a slot 34 therein which is adapted to receive the end 35 of the pawl 31. A spring 36 fastened to the jogger cam and to the pawl 31 pulls the pawl towards the sleeve 33.

The jogger lever 37 is pivoted on the stud shaft 28 and carries a roller 38 which is adapted to ride on the jogger cam 29' and

operate the jogger lever, Figs. 5, 7, 9. A spring 37' is connected to the jogger lever 37 and holds the roller 38 against the cam. A jogger 39 is provided with a foot 40 and is pivoted at 42, Figs. 5 and 7, to the upper end 73 of the jogger lever 37. A spring 43 holds the jogger in operative position on the bed of the machine to engage a magazine on the delivery tapes 58.

A cam 44 fixed to the sleeve 29 is adapted to 75 bear against the roller 45 on an arm 45' mounted on the discharge roller shaft 46, Fig. 9. As the high side 47 of the cam 44 strikes the roller 45 the shaft 46 is given a part turn causing the discharge rollers 48 89 mounted on the arms 48' fixed to the shaft 46 to be raised and allow the magazine to pass from the machine. Stop fingers 50 on the finger bracket 49 pivotally mounted on the shaft 46 are raised or lowered by means of the arm 51 carrying the roller 52 which contacts with the stop finger cam 53. A beveled gear 54 fixed to the shaft 6 meshes with a gear 55 fixed to a transverse shaft 56 carrying rollers 57 and driving tapes 58 which carry the magazine from the feeding end 59 of the machine through the various positions and off the machine to a delivery rack 60, Fig. 2.

The operation of the device is as follows: 95 Printing devices are stacked in the magazine 9 and certain of the devices are provided with tabs for operating the jogging mechanism. Magazines, newspapers or other articles to be addressed are fed through the machine to printing position and then off the machine 100 to the table or rack 60. All printing devices will depress the tripper pawl 11 as they pass to printing position and this depression of the tripper pawl will disengage the tripper 12 from the latch lever 15, but this is all that 105 will happen unless the printing device is provided with a tab, because the high part of the restoring cam 23 which then engages the roller 22 is of sufficient length to continue this engagement while the printing device is riding over the tripper pawl. After the printing device rides off of this pawl the spring 16 restores the tripper and the pawl to normal position, Fig. 6. But when a printing device provided with a tab rides over the 110 tripper pawl the tab will continue holding the tripper pawl in depressed position long enough for the low part of the restoring cam to come into operative relation with the roller 22 and thereupon the spring 20 will pull rod 17 to the right, Fig. 4, rocking the shaft 19 and swinging the angle lever 21 to carry the roller 22 into operative engagement with the low part of the restoring cam and at the same time swinging the link 24 and the pawl 11 115 releasing arm 27 to permit spring 36 to swing pawl 31, which is pivoted on jogger cam 29' to engage the end 35 with slot 34 in the sleeve 33 fixed to the longitudinal shaft 6. While the high part of the jogger cam 29' engages

120 125 130

the roller 38 on the jogger lever 37 the jogger will remain in normal position, but immediately after the pawl 31 becomes locked to the sleeve 33 the low part of the jogger cam 5 engages the roller 38 and thereupon spring 37 causes the jogger lever and the jogger to move quickly from the position shown in Fig. 5 to the position shown in Fig. 7 and jog the magazine. Then the high part of the 10 continuously revolving cam 23 engages roller 22 and swings the angle lever 21 and rocks the shaft 19, and the angle lever swings the link 24 and the pawl releasing arm 27 to release the pawl 31 from the sleeve 33 which brings 15 the jogger cam to rest with the jogger in normal position shown in Fig. 4. Rocking the shaft 19 swings the arm 18 to the left from the position shown in broken lines in Fig. 4 to the position shown in full lines in Fig. 3 and 20 swings the latch lever 15, permitting spring 16 to reset the tripper and tripper pawl in normal position, Figs. 3 and 6. It will be noted that while a printing device without a tab will depress the tripper pawl the jogging 25 mechanism will not be operated because during the time the printing device is riding over the pawl the roller 22 is operatively engaging the high part of the restoring cam 23, thereby preventing the shaft 19 from rocking; but if the depression of the pawl is continued a little longer by the presence of a tab on a printing device the high part of the cam 23 will travel beyond the roller 22 permitting 30 spring 20 to rock shaft 19 and operate the jogging mechanism as hereinbefore described.

Our invention provides automatic mechanism for jogging a magazine being delivered after the address is printed thereon to indicate the beginning or the ending of a group 40 of magazines, and this jogging mechanism is caused to operate by a tab on the address printing device. Therefore, the addressed magazines will be grouped in exact accordance 45 with the tab classification of the address printing devices.

In the specifications we have referred, for convenience, to a magazine as the article addressed in the machine but this is not to be understood as limiting the invention but should be construed as including a newspaper, a folder or any other article which may be used in connection with this invention.

Changes may be made in the form, construction and arrangement of the parts of the invention without departing from the spirit or sacrificing the advantages thereof and the right is hereby reserved to make all such changes as fairly fall within the scope 60 of the following claims:

We claim:

1. In a printing machine having means for feeding address printing devices and 65 magazines to printing position, means for

carrying the addressed magazines from printing position, a bodily movable jogger, means for moving the jogger to engage and jog a magazine, means for actuating said moving means, and a tripper controlling 70 said actuating means, some of said printing devices being provided with tabs to cause operation of the actuating means.

2. In a printing machines having means for feeding address printing devices and magazines to printing position, means for carrying the addressed magazines from printing position, a jogger, means for operating the jogger, means for actuating said operating means, and a tripper controlling 75 said actuating means, said tripper being adapted to be operated by the printing devices as they pass to printing position and some of said devices being provided with tabs to cause the operation of the actuating 80 means.

3. In a printing machine having means for feeding address printing devices and magazines to printing position, means for carrying the addressed magazines from 90 printing position, a jogger, means for operating the jogger, means for actuating said operating means, and a tripper controlling said actuating means, some of said printing devices being provided with tabs, said tripper being adapted to be released by the printing devices as they pass to printing position and this release being prolonged by the tabs to cause the operation of the actuating 95 means.

4. In a printing machine having means for feeding address printing devices and magazines to printing position, means for carrying the addressed magazines from printing position, a jogger, means for operating the jogger, means for actuating said operating means, and a tripper controlling 105 said actuating means, some of said printing devices being provided with tabs, said tripper being operated by each printing device as it passes to printing position to release the actuating means and said release being prolonged by each tab to cause operation of the actuating means.

5. In a printing machine having means for feeding address printing devices and magazines to printing position, means for carrying the addressed magazines from printing position, a jogger, means for operating the jogger, means for actuating said operating means, and a tripper controlling 115 said actuating means, some of said printing devices being provided with tabs, said tripper being operated by each printing device as it passes to printing position to release the actuating means, there being means to prevent operation of the actuating means while the tripper is operated by a printing device without a tab but permitting operation of the actuating means when the operation of the 120

tripper is prolonged by the presence of a tab.

6. In a printing machine having means for feeding address printing devices and magazines to printing position, means for carrying the addressed magazines from printing position, a jogger, means for operating the jogger, means for actuating said operating means, a tripper controlling said actuating means, some of said printing devices being provided with tabs, said tripper being operated by each printing device as it passes to printing position to release the actuating means and this operation of the tripper and releasing of the actuating means being prolonged by the presence of a tab, means to prevent operation of the actuating means while the tripper is operated by a printing device without a tab, and means for causing operation of the actuating means at the time that the operation of the tripper and release of the actuating means is prolonged by the presence of a tab.

7. In a printing machine having means for feeding address printing devices and magazines to printing position, means for carrying the addressed magazines from printing position, a jogger, means for operating the jogger, means for actuating said operating means and comprising a cam, a tripper controlling said actuating means, some of said printing devices being provided with tabs, said tripper being operated by each printing device as it passes to printing position to release the actuating means, and this operation of the tripper and releasing of the actuating means being prolonged by the presence of a tab, said cam preventing operation of the actuating means while the tripper is operated by a printing device without a tab and permitting operation of the actuating means while the tripper is operated by a tab on a printing device.

8. In a printing machine having means for feeding address printing devices and magazines to printing position, means for carrying the addressed magazines from printing position, a jogger, means for operating the jogger, means for actuating said operating means and comprising a cam, a tripper controlling said actuating means, some of said printing devices being provided with tabs, said tripper being operated by each printing device as it passes to printing position to release the actuating means, this operation of the tripper and releasing of the actuating means being prolonged by the presence of a tab, and constantly active means for operating said actuating means, said cam preventing operation of the actuating means while the tripper is operated by a printing device without a tab and permitting operation of the actuating means while the tripper is operated by a tab on a printing device.

9. In a printing machine having means for feeding address printing devices and maga-

zines to printing position, means for carrying the addressed magazines from printing position, a jogger, means for operating the jogger, means for actuating said operating means and comprising a cam, a tripper controlling said actuating means, some of said printing devices being provided with tabs, said tripper being operated by each printing device as it passes to printing position to release the actuating means, this operation of the tripper and releasing of the actuating means being prolonged by the presence of a tab, and constantly active means for operating said actuating means, said cam preventing operation of the actuating means while the tripper is operated with a printing device without a tab, and permitting operation of the actuating means while the tripper is operated by a tab on a printing device and restoring the actuating means to initial position after it is operated.

10. In a printing machine having means for feeding address printing devices and magazines to printing position, means for carrying the addressed magazines from printing position, a latch lever, a tripper engaging the latch lever and adapted to be operated by the printing device to release the latch lever, said tripper being operated by each printing device as it passes to printing position and this operation being prolonged by the presence of a tab on a printing device, a rock shaft, a jogger, means for operating the jogger, means operated by the rock shaft for operating the jogger operating means, constantly active means connected to the latch lever for operating the rock shaft, and a cam preventing operation of the rock shaft while the tripper is released from the latch lever by a printing device without a tab and permitting operation of the rock shaft while the tripper is held in released position by a tab on a printing device.

11. In a printing machine having means for feeding address printing devices and magazines to printing position, means for carrying the addressed magazines from printing position, a latch lever, a tripper engaging the latch lever and adapted to be operated by the printing device to release the latch lever, said tripper being operated by each printing device as it passes to printing position and this operation being prolonged by the presence of a tab on a printing device, a rock shaft, a jogger, means for operating the jogger, means operated by the rock shaft for operating the jogger operating means, constantly active means connected to the latch lever for operating the rock shaft, a cam preventing operation of the rock shaft while the tripper is released from the latch lever by a printing device without a tab and permitting operation of the rock shaft while the tripper is held in released position by a tab on a printing device.

device, and means operative by said cam for restoring the parts to initial position after the operation of the jogger.

12. In a printing machine having means for feeding address printing devices and magazines to printing position, means for carrying the addressed magazines from printing position, a bodily movable jogger, a cam for operating the jogger to engage and jog a magazine, and means controlled by a tab on a printing device for operating the jogger cam.

13. In a printing machine having means for feeding address printing devices and magazines to printing position, means for carrying the addressed magazines from printing position, a bodily movable jogger, a constantly rotating shaft, a cam loosely mounted on the shaft for operating the jogger to engage and jog a magazine, and means controlled by a tab on a printing device for locking the cam to the shaft.

14. In a printing machine having means for feeding address printing devices and magazines to printing position, means for carrying the addressed magazines from printing position, a jogger, a constantly rotating shaft, a cam loosely mounted on the shaft for operating the jogger, and means controlled by a tab on a printing device for locking the cam to the shaft, said means comprising a sleeve rigid with the shaft, a pawl pivotally mounted on the cam and adapted to make locking engagement with the sleeve, means for holding the pawl out of engagement with the sleeve, means for releasing the pawl, and means for causing the pawl when released to engage the sleeve.

15. In a printing machine having means for feeding address printing devices and magazines to printing position, means for carrying the addressed magazines from printing position, a jogger, a constantly rotating shaft, a cam loosely mounted on the shaft for operating the jogger, means controlled by a tab on a printing device for locking the jogger cam to the shaft, a restoring cam fixed to the shaft, and means operated by the restoring cam for releasing the jogger cam from the shaft.

16. In a printing machine having means for feeding address printing devices and magazines to printing position, means for carrying the addressed magazines from printing position, a jogger, a constantly rotating shaft, a cam loosely mounted on the shaft for operating the jogger, means for locking the jogger cam to the shaft, another cam fixed to the shaft, a rock shaft, means controlled by a tab on a printing device for operating the rock shaft, and means controlled by the rock shaft for causing said fixed cam to operate said locking means.

17. In a printing machine having means for feeding address printing devices and mag-

azines to printing position, means for carrying the addressed magazines from printing position, a jogger, a constantly rotating shaft, a cam loosely mounted on the shaft for operating the jogger, means for locking the jogger cam to the shaft, another cam fixed to the shaft, a rock shaft, means controlled by a tab on a printing device for operating the rock shaft, means controlled by the rock shaft for causing said fixed cam to operate said locking means, and means connected with the rock shaft and operated by said fixed cam for restoring the parts to initial position.

18. In a printing machine having means for feeding address printing devices and magazines to printing position, a bed, means for carrying the addressed magazine from printing position and over the bed, and means controlled by a tab on a printing device for jogging the magazine bearing an impression from said tabbed printing device and comprising a jogger, and a lever pivotally connected to the jogger and operable to move the jogger forward to engage and jog the magazine and back to initial position.

19. In a printing machine having means for feeding address printing devices and magazines to printing position, means for carrying the addressed magazines from printing position, a latch lever, a tripper engaging the latch lever and adapted to be operated by a printing device to release the latch lever, said tripper being operated by each printing device as it passes to printing position and this operation being prolonged by the presence of a tab on a printing device, a rock shaft, a rod connected to said latch lever and said rock shaft, a continuously rotating shaft, a jogger cam loosely mounted on said continuously rotating shaft, a sleeve fixed to said continuously rotating shaft and having a slot therein, a jogger lever adapted to be reciprocated during rotation of the jogger cam, a pawl pivoted on the jogger cam, means operated by the rock shaft to cause the pawl to engage said slot and lock the jogger cam to the shaft, and a jogger pivotally connected to said jogger lever for jogging the magazine which received an impression from the printing device carrying the tab which caused the operation of the jogging mechanism.

20. In a printing machine having means for feeding address printing devices and magazines to printing position, means for carrying the addressed magazines from printing position, a latch lever, a tripper engaging the latch lever and adapted to be operated by a printing device to release the latch lever, said tripper being operated by each printing device as it passes to printing position and this operation being prolonged by the presence of a tab on a printing device, a rock shaft, a rod connected to said latch lever and said rock shaft, a continuously

rotating shaft, a jogger cam loosely mounted on said continuously rotating shaft, a sleeve fixed to said continuously rotating shaft and having a slot therein, a jogger lever adapted to be reciprocated during rotation of the jogger cam, a pawl pivoted on the jogger cam, means operated by the rock shaft to cause the pawl to engage said slot and lock the jogger cam to the shaft, a jogger pivotally connected to said jogger lever for jogging the magazine which received an impression from the printing device carrying the tab which caused the operation of the jogging mechanism, and a cam fixed to said constantly rotating shaft and operating to release the jogger cam from said shaft and restore the parts to initial position.
